CLAIM

The ornamental design for a roach clip, substantially as shown and described.

DESCRIPTION

FIG. 1 is a front elevational view of a roach clip showing my new design.

FIG. 2 is an elevational view of the right side thereof; the left side being a mirror image of the right side.

FIG. 3 is a top plan view thereof.

FIG. 4 is a front elevational view thereof shown in the open condition.

The claimed device is used for holding cigarettes or like articles.
